DEVICE FOR CLEANING, POLISHING AND BEATING

Julius Fassio, 1135 Francisco St., San Francisco, Calif.
Filed Oct. 21, 1957, Ser. No. 691,277
2 Claims. (Cl. 15—97)

This invention relates to a device for cleaning, polishing and beating.

One of the more laborious tasks in the home is the cleaning of pots and pans. This often must be done by hand because they generally cannot be suitably cleaned in mechanical dishwashers. There is a demand for a device which will facilitate the cleaning of pots and pans which can also be used for other purposes.

In general, it is an object of the present invention to provide a device for cleaning and polishing pots and pans and which can be used for other household purposes such as beating, or the like.

Another object of the invention is to provide a device of the above character which is mounted in such a manner that it can be placed in an out-of-the-way position when not in use and still be readily accessible.

Another object of the invention is to provide a device of the above character which can be operated with both hands free.

Another object of the invention is to provide a device of the above character in which the same drive means can be used for operating different attachments.

Another object of the invention is to provide a device of the above character in which the attachments are readily removable.

Another object of the invention is to provide a device of the above character in which the coverings for the scouring or cleaning attachments can be readily changed.

Another object of the invention is to provide a device of the above character in which the scouring or cleaning attachment is substantially impervious to liquids and, therefore, will not become foul smelling when used for such operations as cleaning pots and pans.

Additional objects and features of the invention will appear from the following description in which the preferred embodiment has been set forth in detail in conjunction with the accompanying drawing.

Referring to the drawing:

FIGURE 1 is a front elevational view of a conventional household sink upon which a device incorporating my invention is mounted;

FIGURE 2 is a cross-sectional view taken along the line 2—2 of FIGURE 1;

FIGURE 3 is an enlarged view, partly in cross-section, showing a portion of the drive means and the scrubbing attachment mounted thereon;

FIGURE 4 is a cross-sectional view taken along the line 4—4 of FIGURE 3; and

FIGURE 5 is a view, partly in cross section, showing a portion of the drive means and a beating attachment mounted thereon.

The device incorporating my invention and illustrated in FIGURES 1 through 4 of the drawing is comprised of drive means 11 and a cleaning or scouring attachment 12. The drive means consists of an electric motor 13 of any suitable type such as one operated on 110 volts A.C. and having an output shaft speed of approximately 3600 r.p.m. The electric motor is mounted within the cabinet 14 in any suitable manner such as by suspending it in the cabinet as shown.

The cabinet contains a sink 16 and is provided with a front door 17 to provide access to the electric motor 13 and other parts of the sink. The electric motor drives a flexible cable 18 which is mounted in a flexible conduit

2

19 and is connected to a speed reducer 21. The speed reducer may be of any suitable type which will reduce the speed. It is, however, desirable that the speed reducer reduce the speed of the cable to the desired speed such as from approximately 3600 r.p.m. to a speed of approximately 600 r.p.m. The speed reducer unit, as shown, includes a housing 22 which is provided with a cylindrical extension 23. The cylindrical extension serves as a hand grip as hereinafter described. The output shaft of the speed reducer extends through an extension 22a of the housing and is connected to a connecting member 26. The connecting member consists of a cylindrical threaded portion 26a and a flange 28. The flange 28 has a diameter substantially greater than the diameter of the threaded portion 26a and, therefore, the outer margins of the flange extend radially and beyond the axis of rotation of the connecting member 26.

It is readily apparent that different types of attachments can be mounted on the connecting member 26.

20 For example, one type of attachment which is particularly useful is the cleaning or scouring attachment 12 shown in FIGURES 1 to 4 of the drawing. As shown in the drawing, the cleaning or scouring attachment 12 consists of a hard core 31 of suitable material such as aluminum which is provided with a bore 32. The outer end of the bore is threaded to accommodate the threaded portion 26a of the connecting member 26. The core is preferably cylindrical in shape and is covered with a thick layer 33 of a suitable resilient material such as sponge rubber. Since certain resilient materials such as sponge rubber are particularly absorbent, an additional relatively thin layer of relatively resilient yet impervious material covers the outer surface of the layer 33. Any suitable material may be used for the layer 34 such as natural or synthetic rubber. As shown, the layer 34 is provided with widely spaced ribs 36 which extend in directions at right angles to the axis of rotation of the attachment member 12.

40 A suitable scrubbing or polishing element 37 is detachably mounted on the exterior surface of the layer 34. As can be seen from the drawing, the scrubbing element is in the form of a cover and may be held in place by suitable means such as by an elastic member 38 secured in a hem in the inner margins of the cover defining the opening 39 through which the cover is mounted. The scrubbing element can be formed of any suitable material such as stainless steel mesh or cloth impregnated with an abrasive.

45 A spring clamp 41 is mounted on the flexible conduit 50 19 for cable 18 and consists of a collar 42 which is fastened to the conduit by suitable means such as a set screw 43. The collar is provided with a flange 44 extending radially from the axis of the collar. Outwardly-bowed spaced spring members 46 are mounted on the collar and extend longitudinally of the cable in a direction towards the speed reducing unit 21.

55 Means is provided for controlling the operation of the motor 13 and consists of a cord 51 which has one end connected to a suitable power outlet as shown and the other end connected to a control unit 52. Another cord 53 leads from the control unit to the motor 13. The control unit is of a type well known to those skilled in the art and includes a foot operated pedal 54 and a suitable rheostat 56 whereby the motor 13 can be stopped and started by operation of the foot pedal 13 and the speed of the motor controlled by varying the depression of the foot pedal 54.

60 As shown in the drawing, the rear ledge 57 of the sink 16 is provided with an opening 58 of a predetermined size through which the cylindrical extension 23 of the speed reducer extends. The size of the housing 22

for the speed reducer is such that the speed reducer can rest on the rear ledge of the sink.

Operation of my device may now be described briefly as follows: Let it be assumed that the device is in the position shown in FIGURES 1 and 2 and that it is desired to use the device for cleaning pots and pans in the sink. The device is first grasped by the hand around the housing 22 for the speed reducer and the speed reducer and the attachment connected thereto is lifted from the sink until the spring members 46 are pulled through the hole 58 and the flange 44 engages the lower surface of the rear ledge 57. It is readily apparent that the outwardly-bowed spring members 46 will now serve to prevent the cable from slipping back down through the hole 58 and pulling on the speed reducer.

In use, the device is grasped by one hand about the cylindrical extension 23 and the other hand is used for holding the pot during the cleaning operation. The foot pedal 54 is then operated to cause energization of the motor and rotation of the scrubbing or cleaning attachment 12. As hereinbefore described, the speed of rotation of the scrubbing element is controlled by the amount of depression of the foot pedal 54.

It is also readily apparent that rotation of the scrubbing element 22 rapidly cleans and buffs the pot or pan being cleaned. The scrubbing element is chosen for the particular task undertaken. For example, if pots are being cleaned, it is often desirable to use a stainless steel mesh. The stainless steel mesh readily removes food or burned particles from the surface of the pot or pan. The impervious layer of material 34 prevents the sponge rubber layer 33 from absorbing any food particles and the like and, therefore, prevents the scrubbing element from decomposing or becoming foul smelling. The ribs 36 provided on the impervious layer 34 firmly engage the scrubbing element on cover 37 so that the scrubbing element of the cover will rotate with the remainder of the attachment.

After the pot has been cleaned, it is only necessary to rinse off the scrubbing element to remove any food particles in the stainless steel mesh after which the device can be placed in its conventional out-of-the-way position by pressing of the cable to force the spring-like members 46 through the opening 58 down into the cabinet 14. After this has occurred, the remainder of the device can be lowered through the opening 58 until the housing 22 of the speed reducer again rests upon the ledge 57.

If desired, it is readily apparent that instead of mounting the device upon a sink, the device may be placed in a small cubical located above the sink with the foot control mounted on the floor in a convenient location.

It is readily apparent that the drive means 11 can be utilized in conjunction with any number of attachments. For example, as shown in FIGURE 5, it may be utilized for operating an egg beater attachment 61. The attachment, as shown, consists of a housing 62 which encloses suitable gearing well known to those skilled in the art whereby rotation from an input shaft 63 may be transferred to two output shafts 64 without an increase in the speed of rotation between the shaft 63 and the shafts 64.

The shaft 63 is provided with a threaded bore 66 which accommodates the threaded portion of the connecting member 26. The housing 62 is provided with an extension 67 concentric with the input shaft 63 and which rotatably accommodates the input shaft 63. The outer end of the extension 67 is provided with a bore 68 of a diameter which is substantially greater than the diameter of the flange 28 on the connecting member 26. As can be seen from the drawing, the connecting member 26 is threaded into the input shaft 63, the outer end of the extension engages the extension 22a of the housing of the

speed reducer. Engagement of the extension 67 with the extension 22a prevents rotation of the housing 62 as the shaft 63 is rotated. Rotation of the shaft 63 causes rotation of the shafts 64 which, in turn, causes rotation of the beaters 69 secured to the shafts 64.

When it is desired to remove the beater attachment, it is merely necessary to rotate the housing 62 in a direction opposite that of the normal direction of rotation.

It is readily apparent that other attachments can be easily utilized with the drive means disclosed. For example, a brush can be provided with suitable means for mounting on the connecting member 26. Polishing pads, wheels and the like may also be readily secured to the drive means.

15 It is apparent from the foregoing that I have provided a new and improved device for cleaning, scouring, beating and the like. The device is normally in an out-of-the-way position but is readily accessible for use.

I claim:

20 1. In a device of the character described, adapted to be mounted on a sink, motive means adapted to be mounted below the sink, a flexible cable driven by said motive means and adapted to be extended through an opening in the sink, a speed reducing unit having a driving connection with the cable and a driven output shaft, said output shaft being in substantially axial alignment with said driving connection, said speed reducing unit being attached to the cable and adapted to be disposed above the sink, a rotary attachment, means for detachably securing said attachment to the output shaft of the speed reducing unit, said speed reducing unit being enclosed in a housing having a diameter substantially greater than the opening in the sink, said housing having an extending handle portion of substantially less diameter than the opening in the sink and adapted to be received therein, whereby the housing is adapted to normally rest on the sink with the hand grip extending through the opening but can be pulled with the cable through the opening for purposes of using the rotary attachment, and releasable securing means affixed to said cable at a point substantially spaced below said opening in the sink when said speed reducing unit is received in the opening, whereby when the speed reducing unit is removed from the opening and the device is in use the cable is prevented from dropping through the opening by operation of the securing means at the opening.

40 2. A device as in claim 1 wherein said releasable securing means comprises a clamp mounted on said cable, said clamp including a flange and bowed-out resilient members secured to the flange, the bowed-out resilient members being adapted to extend through and engage the opening in the sink.
